PHOTOFFLASH LAMP

Edward G. F. Arnott, Upper Montclair, and Russell H. Atkinson, North Arlington, N. J., assignors to Westinghouse Electric Corporation, East Pittsburgh, Pa., a corporation of Pennsylvania

Application September 1, 1954, Serial No. 453,640

5 Claims. (Cl. 67—31)

This invention relates to the manufacture of SM type photoflash lamps and, more particularly, to an improved and simplified igniter construction.

The present method of igniting the primer in Speed Midget or so-called SM photoflash lamps, which are lamps having a paste primer with no other combustible material, such as metal foil, and for which the present invention is particularly applicable, consists of passing a current through a fine tungsten filament which is thus heated to incandescence. The filament is mounted on two heavier lead wires which are coated with a primer material at the junction of the filament and lead wires. The heat from the incandescent filament causes a highly exothermic chemical reaction from which the high intensity flash is derived. The main difficulties encountered in manufacture and operation are:

(a) Mounting the fine tungsten filament is a painstaking operation.

(b) The filament will not be heated at a sufficiently rapid rate if the flashgun batteries are low.

(c) Base contact in the flashgun must be good. Socket contacts must make firm contact with the corresponding socket lead.

It is the general object of this invention to avoid and overcome the foregoing and other difficulties of and objections to prior art practices by providing a very positive SM lamp ignition system wherein the filament is eliminated.

It is another object to simplify the method of manufacturing SM photoflash lamps so that the bulbs thereof may be exhausted and gas filled, simultaneously with the connection of plastic bases thereto.

It is a further object to provide an SM lamp primer arrangement which is adapted to be ignited by a high voltage spark discharge.

The aforesaid objects of the invention, and other objects which will become apparent as the description proceeds, are achieved by providing an SM photoflash lamp having a plastic base connected to a bulb and provided with leads, at least one of which is insulated, and the inner ends of which are bridged by a primer. Also provided is a method for manufacturing such a lamp.

For a better understanding of the invention, reference should be had to the accompanying drawing wherein:

Fig. 1 is an elevational view of a lamp embodying our invention, a circuit for igniting such a lamp being indicated diagrammatically;

Fig. 2 is a fragmentary axial sectional view of the lamp of Fig. 1, to a larger scale.

Fig. 3 is an expanded, fragmentary, sectional view of the primer-lead portion of the lamp shown in Fig. 2.

Fig. 4 is an elevational view of a modified form of mount for a lamp such as shown in Fig. 1;

Fig. 5 is an elevational view of another modification of a mount for a lamp as shown in Fig. 1.

With specific reference to the form of the invention illustrated in the drawing, in first considering Figs. 1, 2

2

and 3, there is shown a photoflash lamp 21 comprising an envelope or bulb 22 of radiation-transparent material such as glass. The edge of the neck 23 of said bulb 22 is embedded in a plastic block forming a base 24. A pair of leads 25 and 26, are employed, the latter extending through the base 24 to provide a center contact 20. The former is shown bare, and extends from a side of the base, where it forms a lateral prong 27. The prong 27 may unite with a side plate, such as illustrated in Fig. 15 of copending Rively application Ser. No. 358,415, filed May 29, 1953, and owned by the assignee of the present application, and designated by the character 75, or with a band, such as that designated by the reference character 75^b of Fig. 17 of the copending Rively application.

The portion of the lead 26 interior of the bulb 22 and which extends above the plastic of the base 24, is coated with porous insulating material 35 of any desired character, such as the oxide of the metal itself. The lead 25 may be similarly insulated, if desired, but this is not essential. This insulating material is desirably provided by forming the lead 26 of aluminum, or with an aluminum surface, which is oxidized to form an adherent coating of porous aluminum oxide. Other possible base metals are nickel, tantalum and other suitable metals, the oxide of which is insulating. Alternatively, a dielectric other than an oxide of the base metal may be coated onto the high voltage lead, providing of course that such a dielectric has a relatively low breakdown strength to facilitate the setting up of the spark discharge. For example, graphite may be embedded in polystyrene or methyl methacrylate and coated onto one or both of the leads.

Connecting the inner ends of the leads 25 and 26, which are desirably bent to point toward one another, is disposed a mass of primer material 28, which may be conventional such as a paste formed of zirconium powder, or other suitable metal, and an oxidizing agent, thereby completing the mount 30. The bulb 22, the neck of which is cemented to the base by the plastic material of the base 24, also encloses an atmosphere of oxygen or other combustion-supporting gas such as a suitable oxide of nitrogen, for example.

The invention may be described, using aluminum as an example, but other suitable metals can be treated in a similar manner. The oxide-coated lead or leads is (or are) prepared by an anodizing process in which a length of aluminum wire is made the anode and an inert electrode is made the cathode. The electrolyte is about 0.1 molar sulfuric acid. A current of 2-3 amps. at 30 volts is passed for about 15 secs. at which time the wire is withdrawn, washed with hot water, and then air dried. This coated wire is then mounted along with a length of uncoated aluminum wire. Primer is applied so that the dried bead bridges the gap and makes contact with both leads. The assembly is then mounted in a lamp. In operation the oxide-coated lead may be connected to the high voltage source and the other lead to ground. The anodizing process, as described, will produce an aluminum oxide coating of about 1 mil thickness, which is the preferred thickness for such a coating, although the oxide-dielectric coating may vary between about 0.5 mil and 5 mils thickness. Below 0.5 mil thickness the coating tends to become discontinuous so that the coated primer may contact the aluminum base metal of the lead. Above 5 mils thickness the aluminum oxide tends to chip off thus creating low resistance paths and eliminating the spark discharge.

As a specific embodiment, the leads 25 and 26 may project 1/2" above the base 24 into the bulb and these leads are preferably separated by 1/2", except at their inwardly projecting extremes, to insure against a spark

discharge between the leads at any point other than at their inner ends. The lead inner ends may have a gap therebetween of $\frac{1}{4}$ ", for example. This dimension is not critical provided some gap is maintained, and this dimension is more governed by proper suspension of the primer bead 28. 50 mg. of primer material may be suspended between the inwardly extending portions of the leads and this primer material may consist of a mixture of zirconium powder and potassium perchlorate in the proportion of 75-25. The envelope may enclose an oxygen atmosphere at a pressure of 600 mm. Other suitable materials may be used as a primer such as powdered magnesium and an oxidizer, for example.

The wiring diagram of Fig. 1 indicates how the lamp there illustrated may be fired. In this diagram, the reference 31 represents a source of power, which may be a 22½ volt hearing-aid dry cell battery. Connected to the battery is a resistor 32, of preferably about 10,000 ohms, and a condenser 33, of preferably about 50 microfarads capacity, said condenser being across the battery terminals with the resistor in series.

The condenser terminals are, in turn, connected through a switch 34 to the primary winding 36 of a step-up transformer 37. The secondary winding 38 of said transformer has one terminal connected to a terminal of the primary winding 36, and the other terminal connected to the insulated lead 26 at the outer contact portion thereof at the center of the base 24 of the lamp 21. The prong 27 may be grounded, as indicated at 39, if desired. With this arrangement, the condenser is slowly charged through the resistor 32 and is in condition for delivering a desired surge of electrical energy to the primary winding 36 of the transformer upon closing the switch 34.

The ratio between the turns of the primary and secondary windings is desirably such that a potential of at least 10,000 volts and preferably 20,000 volts is delivered to the base 24 on closing the switch 34, to thereby produce a spark discharge between the inner end of the lead 26 and the primer material 28, across the gap consisting of the porous dielectric material 35, thereby igniting the primer.

Although we have diagrammatically disclosed means for igniting a lamp embodying this invention, yet practical embodiments of such means are illustrated in Figs. 5 and 6 of the copending application of Rively, previously referred to.

The mount 39^a shown in Fig. 3 is like the mount 30 of Figs. 1 and 2, except that both of the leads 25^a and 26^a extend from the base 24^a, toward one another, to their inner ends which are bridged by a mass of primer 28^a. Also, both are shown coated with porous insulating material 35^a, although only one lead need be so coated. Such a mount may be assembled with a bulb to make a photoflash lamp like the mount 30 of Figs. 1, 2 and 3.

The mount 39^b shown in Fig. 4 is like the mount 30 of Figs. 1, 2 and 3, except that both of the leads 25^b and 26^b are coated with a porous insulating material 35^b only at their inwardly projecting extremities where the mass of primer 28^b is supported. Such a mount when incorporated into a lamp, as shown in Fig. 1, will function exactly the same since only that portion of the leads about which the primer is to be coated need be provided with an insulating or dielectric coating. Also the leads 25^b and 26^b traverse the base in a substantially parallel fashion, terminating in the bottom of the base in two contact electrodes 40 and 41, across which the igniting potential is applied. It should be noted that for manufacturing convenience the entire portion of at least one lead which projects into the bulb may be provided with a dielectric coating. This eliminates the need for accurate positioning of the lead when applying the dielectric coating thereto.

Normally where dielectrics are employed their purpose is to insure against a breakdown and to insure that a spark discharge is not set up. In the instant application,

however, the dielectric is so applied as to insure that a spark discharge will be set up and that the dielectric will break down. Aluminum oxide is particularly adapted as a dielectric in the instant application, for microscopic examination of a 1 mil coating of aluminum oxide reveals that there exists a plurality of crevices or rifts in the aluminum oxide which crevices parallel the length dimension of the wire electrode. These crevices are of no more than 1 micron in width and occur on an average of about one every 50 microns when the dielectric coating is prepared in the previously described manner. When the primer material is coated onto the anodized aluminum lead the surface tension of the primer is sufficient that these crevices or rifts in the aluminum oxide coating will not be filled, but will be bridged by the primer. Thus, there exists through the aluminum oxide coating a series of air gaps which are particularly adapted to facilitate the setting up of a spark discharge through the dielectric.

In the operation of the lamps of this invention one of the leads on firing is at a very high potential and the other lead is at ground potential. If the dielectric coating is applied either to both leads or to the high potential lead, the primer bead will in effect be at ground potential since the primer is a relatively good conductor. The dielectric coating will break down under the applied voltage and a spark discharge will be formed. The primer bead is suspended between two leads, as hereinbefore explained, and when drying the weight of the bead apparently causes stress pores, fissures or rifts to occur in the primer bead, which pores extend through the bead from one lead to the other by means of devious stress paths. These pores constitute paths through which oxygen may be supplied to the vicinity of spark discharge, which is set up at the dielectric-primer interface, to initiate firing of the primer.

The breakdown voltage for the dielectric coating should not exceed about 1000 volts where the applied potential is 10,000 to 20,000 volts if firing of the lamp is to be reproducible. It should be understood that under ideal conditions the breakdown strength for the dielectric might be as high as 95% of the voltage which is available to create the spark, but under such conditions a reproducible spark cannot be obtained. The minimum breakdown strength for the dielectric should be not less than the dielectric strength of the air and the minimum breakdown strength for the dielectric as used in this application should be at least 100 volts. It should be understood that these dielectric breakdown strength limitations are only given for a practical working embodiment and can be exceeded in either extreme under ideal conditions, which are not readily reproducible on a production basis.

A lamp such as illustrated in Fig. 1 is desirably manufactured using apparatus such as illustrated in Figs. 13 and 14 of said Rively application. The plastic material desirably employed to make the base 24 may be that designated by the trademark "Vinnapas." This is so-called "sealing" plastic manufactured by Dr. Alexander Wacker, Gesellschaft fur Electrochemisch Industrie, G. m. b. H., 22 Prinzregentenstrasse, Munich, Germany. This is 45% polyvinyl acetate, 25% powdered talc and 30% micro-crystalline wax. However, other solid plastic materials which have melting points lower than that of the bulb 22 to which connected, and low enough to permit softening prior to ignition of the primer 28, may be employed, as by melting and casting to shape.

The apparatus of Fig. 12 of the Rively application referred to may serve for applying primer to the leads 25 and 26, although it will be understood that such primer may be applied in any desired manner as is well understood by those skilled in the art.

After application of the paste primer 28 to the leads 25 and 26 over the dielectric coating 35 on the latter, the primer is allowed to dry and the mount so constructed is then reversed in position. The base 24 may be inserted in a cup such as designated 59 mounted on the

upper end of a reciprocable rod 61 and carrying a light spring 62 in its interior, as illustrated in the copending Rively application, hereinbefore referred to. The spring 62 resiliently urges a disk into engagement with the bottom of a supported base 24. The cup is disposed in an exhausting and gas-filled chamber 63, which for the purpose is connected to an exhaust and gas-filling system, as by means of a pipe 64. Leakage between the rod 61 and the lower wall of the chamber is prevented by means of a sealing bellows arrangement 65, 10 desirably the so-called "sylphon" type.

In the chamber 63, as illustrated in said copending Rively application, is mounted a coil of oxygen-resisting Nichrome or other heating wire 66, surrounding the cup 59. Leads 67 and 68 connect the wire 66 to a source of power by energizing the same to soften quickly the plastic base 24, without igniting the primer 28, while said base is supported resiliently in the cup 59. The chamber 63 opens upwardly and is closed partially by a rubber or other resilient cover 69, apertured as indicated at 71 to receive the neck 23 of the bulb 22, while nesting with the main or bulbular portion thereof to provide an air-tight engagement.

The manner of operating the apparatus of said copending application for uniting a base to a bulb after exhausting and gas-filling is as follows: A mount comprising a plastic base 24 and leads 25 and 26, at least one of which is oxidized or otherwise insulated, carrying a mass of primer material 28, is placed with the base resting on the spring 62 and disposed in the cup 59. A bulb 22 15 is then placed over the primer 28 to close the aperture 71. The air in the chamber 63 and connected bulb 22 is then exhausted, while the coil 66 is energized to soften the plastic base 24.

After exhausting to the desired extent, oxygen or other combustion-supporting gas is introduced into the chamber 63 from whence it passes to the bulb 22. The bulb during the operation is held in place by a suitable chuck 72. When filling gas at the desired pressure has been introduced and the plastic base 24 sufficiently softened, the rod 61 is raised to push the base 24 into sealing engagement with the lower end of the neck of the bulb. The apparatus and formed lamp are then allowed to cool and the lamp removed and replaced by parts of other lamps for a repetition for the operation.

It will be recognized that the objects of the invention have been achieved by providing a very positive SM type photoflash lamp wherein the filament is eliminated and in which the primer is ignited by a high voltage spark. Also provided is a method for making such lamps.

While in accordance with the Patent Statutes, one best known embodiment of the invention has been illustrated and described in detail, it is to be understood that the invention is not limited thereto or thereby.

We claim:

1. A photoflash lamp comprising a radiation-transmitting bulb with a neck, a block of plastic forming a base in which the edge of said neck is embedded, a pair of spaced metallic leads traversing said base and projecting inwardly within said bulb, a dielectric coating on at least one of the inwardly projecting extremities of said

leads, a paste primer supported by and between said lead inwardly projecting extremities and in contact therewith, said dielectric coating insulating the metallic portions of the said dielectric coated lead portions from said paste primer, and a combustion supporting atmosphere contained within said bulb.

2. A photoflash lamp comprising a radiation-transmitting bulb with a neck, a block of plastic forming a base in which the edge of said neck is embedded, a pair of spaced metallic leads traversing said base and projecting inwardly within said bulb, a dielectric coating on the inwardly projecting extremity of one of said leads, a paste primer supported by and between said lead inwardly projecting extremities and in contact therewith, said dielectric coating insulating the metallic portion of said dielectric coated inwardly projecting lead extremity from said paste primer, and a combustion supporting atmosphere contained within said bulb.

3. A photoflash lamp comprising a radiation-transmitting bulb with a neck, a block of plastic forming a base in which the edge of said neck is embedded, a pair of spaced metallic leads traversing said base and projecting inwardly within said bulb, a porous dielectric coating on the inwardly projecting extremity of one of said leads, a porous paste primer bridging said lead inwardly projecting extremities, said dielectric coating insulating the metallic portion of said dielectric coated inwardly projecting lead extremity from said paste primer, and a combustion supporting atmosphere contained within said bulb.

4. A photoflash lamp comprising a radiation-transmitting bulb with a neck, a block of plastic forming a base in which the edge of said neck is embedded, a pair of spaced metallic leads traversing said base and projecting inwardly within said bulb, dielectric coatings on the inwardly projecting extremities of said leads, a paste primer supported by and between said lead inwardly projecting extremities and in contact therewith, said dielectric coatings insulating the metallic portion of said dielectric coated inwardly projecting lead extremities from said paste primer, and a combustion supporting atmosphere contained within said bulb.

5. A photoflash lamp comprising a radiation-transmitting bulb with a neck, a block of plastic forming a base in which the edge of said neck is embedded, a pair of spaced aluminum leads traversing said base and projecting inwardly within said bulb, a dielectric coating of aluminum oxide on the inwardly projecting extremity of one of said leads, a porous paste primer supported by and between said lead inwardly projecting extremities and in contact therewith, said dielectric coating insulating the metallic portion of said dielectric coated inwardly projecting lead extremity from said paste primer, and a combustion supporting atmosphere contained within said bulb.
